His Attorney.

UNITED STATES PATENT OFFICE

HALSTED BAILEY, OF PITTSFIELD, MASSACHUSETTS, ASSIGNOR TO GENERAL ELECTRIC COMPANY, A CORPORATION OF NEW YORK.

ELECTRICAL APPARATUS.

Application filed September 26, 1918. Serial No. 255,746.

To all whom it may concern:

Be it known that I, HALSTED BAILEY, a citizen of the United States, residing at Pittsfield, in the county of Berkshire, State of Massachusetts, have invented certain new and useful Improvements in Electrical Apparatus, of which the following is a specification.

My invention relates to a switch mechanism which is adapted to connect selected conductors or windings in desired relations and it has for its object the provision of an improved form of switch mechanism which is rugged, durable and readily manufactured.

Prior to my invention, it has been the practice in electrical apparatus, such as transformers and the like whose windings were to be connected in various relations, in order to yield voltages of different desired ratios, to provide them with terminal boards on which the taps leading to the windings can be connected as desired. These terminal boards were frequently submerged beneath the insulating medium surrounding the windings in order better to insulate the connections; all of which added to the inconvenience and uncertainty with which the connections were made at the terminal board.

In the practice of my invention the necessity for the use of terminal boards with their attendant uncertainties is entirely done away with for I have provided a ratio adjusting means to which the various taps may be led and connected in the desired manner by simply manipulating a readily accessible handle or knob to get the desired voltage.

The means provided by my invention is preferably so designed that it can be submerged in the insulating medium which surrounds the windings whose taps are to be connected in desired relations, which medium serves not only more effectually to insulate the parts of the ratio adjusting means but also as a ventilating and arc suppressing medium; thereby greatly increasing the life of the mechanism provided.

For a more complete understanding of the nature and objects of my invention reference should be had to the following detailed description taken in connection with the accompanying drawing in which Fig. 1 shows an electrical apparatus, having windings connected by a ratio adjusting means con-

bodying my invention. Fig. 2 is a diagram showing the manner in which the connections are effected. Figs. 3 and 4 are respectively a perspective and a sectional view of a tap changing device constructed to effect adjustments of the voltage ratios in accordance with my invention. Fig. 5 is a sectional view of a modified form and Figs. 6 and 7 are fragmentary sectional views showing details.

Referring now to Fig. 1, of the drawing, 10 denotes a casing for an electrical apparatus, such as a transformer whose windings 11 are to be connected to yield desired voltage ratios. The casing 10 has a cover 12 through which the ratio adjusting means 13 projects into the cooling and insulating medium 14 which surrounds the windings 11. While the device 13 is shown as projecting through the cover 12, it is obvious that it could have been equally well mounted wholly within the casing 10, access being had by the removal of a cover.

The device is shown in Figs. 3 and 4 as consisting of a supporting frame or tube 15 which may be made of either conducting or non-conducting material but preferably the latter, and which has an upper and lower insulating base, shown at 16 and 17 respectively, for carrying a plurality of contacts 18. These contacts are preferably rods of conducting material inserted parallel to the cylindrical axis of the tube 15 at equal distances from each other along the perimeter of a circle, as indicated in Fig. 2, where the contacts 18 are shown as connected by the six leads 19, 20, 21, 22, 23 and 24 to various sections of the primary winding P of a transformer, the voltage ratio of which is to be varied.

The desired connections are effected by means of a movable contact making member 25 which bridges a pair of contacts 18 in any one of its various positions; the member 25 being preferably designed to fit between the contacts 18 in order positively to secure it in a given position.

It is desirable at all times to secure linear contacts between the member 25 and a pair of contacts 18 since one of the particular problems of my invention is to handle relatively large potential differences between contacts safely in a small space. This may be conveniently accomplished by making the member 25 in a plurality of sections or

rings 26, as shown in Figs. 3, 4 and 5. The contact member 25, to be readily manipulated, is mounted on an offset or eccentric portion of the shaft 27 which is rotatably mounted in the tube or frame 15 and which is preferably coincident with the axis of the tube 15 where the contacts 18 are at equal radial distances from the axis. A knob 28, as shown at the upper end of the tube, is provided so that the shaft may be manually actuated.

The sectionalizing of the contact member 25 is conveniently accomplished as shown in Fig. 6 by supporting individually the annular sections 26' in a flexible manner on the shaft 27. This flexibility is readily effected by resiliently supporting the sections on the offset portion of the shaft 27, where a sleeve 30 is slipped over the offset portion 29 of the shaft 27, to which sleeve spiral springs 31 are secured and over which the annular sections 26' are slipped; such sections being here shown as provided with internal flanges 32 to prevent their displacement, having once been put in place.

In order that the connections affected by the device may be visually indicated, the knob 28 is provided with an indicator; that shown comprises an opening 33 formed in the knob 28 through which may be seen suitable markings placed on the cap plate 34 which is rigidly secured in tube 15. Any suitable indicating device however may be employed.

85 The ventilation of the tap changing device is accomplished by placing large openings 40 and 41 diametrically opposite each other in the side of the tube 15 adjacent the contacts 18 and by providing one or more vertical passages 42 in the bases 16 and 17 respectively; egress for the medium entering the passages 42 being provided by openings 43 placed in the side of the tube 15 at a sufficient distance from the top of the tube 45 to be normally below the surface of the cooling and ventilating medium.

In the modified form of the tap changing device shown in Fig. 5 flexibility for the contact member 25 is provided by making it of a helical spiral spring, as shown at 36, the ends having a conical form as shown at 37, in order to secure a centering effect, when mounted on the offset portion of the shaft 27. In other respects this modified form of 55 device is shown like that in Figs. 3 and 4.

In operation, to change the voltage ratio of the transformer shown the knob 28 is turned to move the member 25 from bridging one pair of contacts 18 to any other de-

sired pair. This change is preferably made when the transformer is not receiving current from the line in order to avoid drawing arcs across the contacts. In Fig. 2 the member 25 is shown as bridging the contacts on leads 23 and 24 which cuts out one section 65 of the winding P. The member 25 may be moved to bridge the contacts on leads 22 and 23 where all sections of the winding P are in service, or to bridge the contacts on leads 19 and 20 where the lowest number of sections of winding P are in service, or to one of the other three positions where an intermediate number of sections are in service.

While I have here shown an embodiment of my invention which is at present the best 75 means known to me for carrying the same into effect, I would have it understood that this is merely illustrative and that I do not mean to be limited thereby to the precise details here disclosed since obvious alterations thereof will appear to those skilled in this art, nor in the choice of recognized equivalents except as defined in my claims hereunto annexed.

What I claim as new and desire to secure 85 by Letters Patent of the United States, is:—

1. A tap changing device comprising a supporting frame having insulating bases therein, contact rods rigidly secured at each end in said bases parallel to the axis of said frame, a rotatable shaft mounted centrally of said contact rods, and a sectionalized bridging member resiliently secured on an offset portion of said shaft and arranged to make linear engagement with said contact 95 rods.

2. A tap changing device comprising a tube having insulating bases therein, contact rods rigidly secured at each end in said bases parallel to the axis of said tube, a rotatable 100 shaft mounted centrally of said contact rods, a manipulating knob having an indicating device secured on said shaft externally of said tube, and a sectionalized annular bridging member resiliently mounted on an offset 105 portion of said shaft.

3. A tap changing device comprising a tube having insulating bases therein, contacts mounted in said bases parallel to the axis of said tube, a rotatable shaft mounted centrally of said contacts, and a bridging member resiliently mounted on said shaft, said shaft coinciding with the axis of said tube, said tube and said bases being provided with ventilating passages.

In witness whereof, I have hereunto set my hand this 21st day of September, 1918.

HALSTED BAILEY.
